UNITED STATES PATENT OFFICE

HANS SCHÖLNHAMMER, OF WAIDHOFEN, AUSTRIA, ASSIGNOR TO MAX LEBER, OF VIENNA, AUSTRIA

TABLE CONVERTIBLE TO A CHAIR

Application filed August 9, 1927, Serial No. 211,668, and in Austria July 27, 1926.

My invention relates to improvements in furniture construction and has reference particularly to that class of furniture which can be converted to different uses by simple manipulation of the parts thereof.

The principal object of this invention is to provide an article of furniture of the class described, which is convertible from a table into a seat and vice-versa, and which is manipulated by the simple operation of a handle.

I accomplish this object by means of a construction embodying certain novel combinations and arrangement of parts hereinabove described in the specification, set forth in the claims and illustratively exemplified in the accompanying drawings, in which, Figure 1 is a perspective elevational view of my improved device arranged as a chair; Figure 2 is a perspective elevational view of the same being converted into a table; Figure 3 is an end elevational view of the device with the parts arranged as a table.

Referring to the drawings, 10 denotes the parallel base beams of an upright standard adapted to hingedly support a table top 11. The standard comprises an inverted U-shaped rear frame 12, the free ends thereof of the parallel arms 13 being fixed in upright position in the upper faces of the base beams 10 adjacent their rear ends. The forward ends of the base beams 10 accommodate upright posts 14, which are beveled downwardly towards the rear at their upper ends, and which are each held in rigid upright position by means of a T-shaped brace 15, the cross head thereof being fixed at its opposite ends in the inner walls of the arm 13 and post 14, while the stem or upright is fixed at its free end in the midportion of the beam 10. The two posts 14 are further tied together in spaced relation by means of a cross bar 16 attached at its ends in the sides of the posts. Tie rods 17 are also arranged front and rear between the sides of the beams 10; and between the front rod 17 and bar 16, a brace 18 is fixed.

The forward pair of uprights, of which the posts 14 are a part, comprise in addition, a pair of arms or extensions 19, which at their

lower ends, are provided with further extensions 20 folding against the posts 14 and pivoted to the latter adjacent the base pieces 10 on pins 21. The portions 19 of the arms are beveled at their lower ends to engage the beveled ends of the posts 14 whereby forward movement of the arms is limited to an upright position, as illustratively exemplified in Figure 2. The upper ends of the arms 19 are inclined towards the front at an angle which will bring the rear walls of the ends flat against the forward sides of the rear standards or frame 12 adjacent the upper end thereof, when the arms 19 are swung to the rear about their pivots 21, as illustratively exemplified in Figures 1 and 2. The upper ends of the arms 19 carry a cross bar 22, which in the table position of the device, supports the forward portion of the table top 11. The upper side of each cross bar 15 is notched at its mid portion to provide a seat 23 for the lower beveled end of the arm 19 when the device is arranged as a chair as shown in Figures 1 and 2. The cross bars 15 are further provided with blocks 24 at the angles of the bars and posts 14 to arrange rests for the free side of the table top 11 in its inclined position.

Referring now to the details of the table top 11, the latter comprises a rectangular frame divided transversely thereof at its midportion by a rail 25, which separates the opening in the top into two parts. Each part of the opening is closed by a separate panel 26, which carries on its under face along the sides adjacent the end and rail pieces 25, a pair of tapered flanges 27, the latter being disposed perpendicular to the under face of the panel and at their forward ends are provided with forwardly and downwardly projecting hook-shaped portions 28 terminating in toe portions 29 bent from the flanges 27 and projecting sidewise beyond the transverse side edges of the panel. The panels 26 are each mounted to pivot about pins 30 carried by hangers or bearing pieces 31 integral with and projecting perpendicularly to the under surface of the table top 11 at positions on the end and center bars 16, which will allow the flanges 27 to fit there-between to receive

the pins 30 about which the whole panel swings to open position, as illustrated in Figure 1. The hangers 31 are arranged more closely to the front of the table top 11, than to the rear, so that as the panel swings forwardly from the top 11, its greater portion will project beyond the latter to provide seating space. The panels 26 are limited in their outward or open positions to a level substantially parallel with the base pieces 10, and this position is made permanent by means of blocks or stop plates 32 arranged on the under face of the table top frame 11 and adapted to be engaged by the toe portions 29 of the flanges 27 as shown in Figure 1. The hinge connections for the top 11 comprise a pair of spaced bars 33 projecting forwardly from the under face at the rear side of the table top and at an angle thereto, to pivot at their free ends about pins 34 which are carried on the outer sides of the arms 13 adjacent their upper ends, as illustrated in Figure 2. The table top 11 is further provided with a stop rod 35 on its under surface adjacent the hinged side, to abut the forward sides of the arms 13, when the top is arranged in its inclined position ready to have the panels swung out to form seats. To prevent the table top from being unintentionally separated from the cross rail or bar 22 when resting thereupon, a spring member 36 is arranged on the under surface of the frame of the top 11 and yieldably engages the bar 22.

To convert the device from a table to a bench or seat, the top 11 is lifted about its hinge connections 33 after releasing the spring 36 from engagement with the bar 22, and the arms 19 swung towards the rear frame 12 until the upper portion rests against it. The table top is then swung downwardly until its front lower edge rests upon the blocks 24. In this position the top is at a rather steep inclination and the seats are formed by swinging the panels outwardly about their pivots until the toe portions 29 engage the blocks 32. It is to be noted especially in this connection that the faces of the panels utilized as a surface to complete the table top in one position, actually become the unused under surface of the panel converted into a seat, as illustrated in Figure 1.

Having now described my invention what I claim and desire to secure by Letters Patent is:

1. In a convertible table and seat, the combination of a hinged table top having a plurality of panels opening out of the same to form seats, and supporting members for the table top, comprising back legs and front legs, each front leg having a pivoted part to swing into contact with the corresponding fixed back leg, whereby the table top may be inclined about its hinge to rest at its free end on the stationary parts of the front legs.

2. A convertible table, as claimed in claim

1, including means for supporting the panels with one of their faces upturned and at an angle to the top when the latter is inclined, and the opposite faces upturned in positions level with the top when the latter is raised to its table position.

3. In a convertible table, the combination of a table top adapted to be swung into a forwardly inclined position; a portion of the said top, being pivotally connected to the rest of the top and adapted to be swung out of the plane of the rest of the top; and a bracket forming ledge on the rear side of the said pivoted portion, adapted to abut against the rear side of the main part of the table top so as to hold the said pivoted portion in a seat forming position.

4. A convertible table the combination of a supporting lower frame containing lateral connecting staves a pair of stationary rear legs fixed to the lower frame; a pair of front legs with a connecting ledge at their upper ends, the front legs being pivotally mounted on said lower frame and adapted for adjustment against the said rear legs; a table top movably connected to the top of the rear legs and supported by the front legs and adapted to be swung into a forwardly inclined position, so as to rest on the said lateral staves of the lower frame; means for locking the connecting ledge of the front legs to the table top, when the latter is in its raised table forming position; a pivoted portion on the said table top adapted to be swung out of the plane of the top; bracket forming ledges on the said pivoted portion to hold it in a seat forming position; and a panel forming portion of the said table top, adapted to serve as a back support if the above mentioned pivoted portion of the table top is swung out into its seat forming position.

In testimony whereof I have signed the name to this specification.

HANS SCHÖLNHAMMER.
